M. L. GRIFFIN

PROCESS OF DISTILLING MATERIALS

Filed March 26, 1920

Martin L. Griffin
Inventor
By his Attorney
Frederick Wright & Hull

UNITED STATES PATENT OFFICE.

MARTIN L. GRIFFIN, OF RUMFORD, MAINE.

PROCESS OF DISTILLING MATERIALS.

Application filed March 23, 1920. Serial No. 368,884.

To all whom it may concern:

Be it known that I, MARTIN L. GRIFFIN, a citizen of the United States, residing at Rumford, in the county of Oxford and State 5 of Maine, have invented a certain new and useful Improvement in Processes of Distilling Materials, of which the following is a specification.

My invention relates particularly to a process 10 of treating waste materials so as to obtain valuable products therefrom notwithstanding the difficulty of handling the same.

The object of my invention is to provide a process by means of which materials, which have a tendency to foam and which are therefore difficult to treat by ordinary processes of destructive distillation, may be subjected to destructive distillation so as to recover valuable by-products without the foaming 20 tendency in any way interfering with the process. A further object is particularly to treat in this way wood pulp waste liquors, as for example those obtained from the manufacture of sulphite pulp or soda pulp, one 25 kind of which is the so-called "black liquor", although it is to be understood that the process is applicable also to waste liquors obtained from the treatment of other natural organic growths such as esparto grass, ordinary straw, cotton straw, stalks of plants, grasses, 30 barks, etc. The object is furthermore to recover as by-products for example, acetone, methyl alcohol, oily materials, sodium acetate and tarry substances.

Again the object is to carry out the process in such a way as to feed the material to be distilled upon a moving surface where the material is completely treated to recover the products of the distillation without the necessity of moving the material relative to the supporting surface during the treatment, thus avoiding the formation of agglomerated masses which would tend to clog the apparatus.

The object is furthermore to decrease the cost of paper manufacture by recovering these by-products.

Still another object is to obtain such by-products continuously and without the necessity of adding porous materials thereto.

Further objects of my invention will appear from the detailed description thereof contained hereinafter.

While my invention is capable of embeddi-

ment in many different forms, for the purpose of illustration I shall describe only one form of my invention hereinafter and while it is capable of being carried out in connection with many different types of apparatus, I have shown only one type of apparatus 55 for use in connection therewith in the accompanying drawings, in which—

The figure is a diagrammatic representation of an apparatus made in accordance 60 with my invention.

In the drawings I have shown diagrammatically a vacuum evaporator 1 in which the dilute black liquor obtained in the manufacture of paper pulp is introduced for evaporation and concentration and where the liquor is concentrated to as thick a consistency as possible. From this point the concentrated liquor passes by a valved pipe 2 into a storage receptacle 3 having a man-hole 4 and a valved outlet pipe 5. The pipe 5 conducts the liquor to a spray pipe 6 which sprays the same along the upper surface of a revolving drum 7 in a distilling chamber or retort 8 having hollow bearings 9 and 10 in its ends to receive a hollow shaft 10 on which the drum 7 is carried. A pulley 11 is provided to drive the drum 7 from any suitable source of power and stationary inlet and outlet pipes 12 and 13 enter the shaft 10 to supply the interior of the drum 75 with a heating medium as for example heated oil which may have a temperature such as to maintain the surface of the drum 80 at from 550° to 700° F. The drum 7 is rotated slowly and the liquor is received 90 thereon in a thin film. Immediately upon being received by the surface of the drum 7 the volatile constituents of the mixture are expelled from the liquor and the carbonization 95 proceeds very rapidly until the carbonization is complete and the dried and carbonized residue carried by the surface of the drum 7 is continually scraped off by a scraper 14 and may be removed from the bottom of the chamber 8 through a door 15 whenever 100 desired. The vapors which are formed by the carbonization of the liquor and which are comprised of steam, acetone, methyl alcohol, etc., pass away by a pipe 16 to a tubular condenser 17 provided with a cooling current of water by means of inlet and outlet pipes 18 and 19 and from which 105 the condensate is conducted by a valved out-

let pipe 20 to a condensate storage receptacle 21 having a man-hole 22 and a valved liquid outlet pipe 23. The uncondensed gases escape from the condensate storage receptacle 21 by means of a valved pipe 24.

While I have described my invention above in detail I wish it to be understood that many changes may be made therein without departing from the spirit thereof.

10 I claim:

1. The process of distilling a wood pulp waste liquor which consists in evaporating it on the surface of an internally heated, rotary

drum in order to distill off the volatile matter, and then condensing said volatile matter. 15

2. The process of distilling a wood pulp waste liquor which consists in evaporating it on the surface of an internally heated rotary drum, condensing the volatile matter evolved, and substantially continuously scraping from 20 the drum the dry residue.

In testimony that I claim the foregoing, I have hereunto set my hand this 20th day of March, 1920.

MARTIN L. GRIFFIN.
